PROCESS FOR CRACKING HYDROCARBON OILS

Frank W. Hall and Harris A. Smith, Port Arthur, Tex., assignors to The Texas Company, New York, N. Y., a corporation of Delaware

Application April 27, 1931, Serial No. 533,042

3 Claims. (Cl. 196—61)

This invention relates to an improved process and apparatus for the conversion of hydrocarbon oil to produce gasoline or motor fuel and more particularly to a process wherein the oil is commingled with hot vapors previously subjected to cracking and the resulting mixture of cracked vapors and vaporized charge is fractionated to produce a desirable gasoline fraction and a heavier liquid fraction composed of partially converted oil and fresh oil for cracking in the vapor phase.

10 In its broadest aspect the invention comprises a process of converting hydrocarbon oils to produce gasoline wherein a clean stock composed of a mixture of partially converted oil and fresh oil which is free from residual and potential coke forming material is continuously evolved and conducted in the form of vapor thru regenerative heating means wherein it undergoes cracking in the vapor phase.

20 The invention also contemplates an improved combination of apparatus which is particularly well adapted for carrying out the method of the invention.

Our invention contemplates a process for treating hydrocarbon oil for the production of gasoline wherein the oil which is to be cracked is heated to a vaporizing temperature and the resulting vapors are passed in succession thru a series of regeneratively heated converters wherein the vapors are brought into contact with hot refractory material arranged in the form of flues or checkerwork within the converters and adapted to heat the vapors to a conversion temperature and maintain them under cracking conditions during their continued passage thru the successive converters. The cracked vapors leaving the converters commingle with fresh incoming charge to subject the vapors to partial condensation and effect distillation of the charge oil so as to produce a combined vapor free from residual or tarry matter and which is subjected to fractionation to form a gasoline vapor fraction and a heavier liquid or reflux condensate consisting of fresh oil and partially converted oil which, due to its freedom from heavy residual fractions, is adapted to form a clean circulating stock suitable for circulating in a vaporous condition thru the converters and to undergo cracking therein without the production of substantial quantities of coke.

50 For our regenerative heating means we prefer to employ a plurality of converters somewhat similar to the regenerative heating stoves used in carburetting water gas or to the type usually employed in connection with blast furnaces in steel mills. Thus, for example, when employing four

converters, the converters are preferably interconnected in such a manner as to permit flowing vapors thru three of them in succession while the fourth is being heated up by blasting or firing until the refractory material has reached a temperature of 1400° F. or higher, following which the heated converter is cut into the system and the coolest converter cut out for reheating. Preferably the vapors are introduced to the coolest converter still remaining in operation and are finally discharged from the hottest or most recently heated converter. When a cooled converter has been cut out of the series for heating, fuel gas may be admitted thereto to displace all the rich cracked hydrocarbon vapors remaining within the converter into suitable receiving means after which combustion is initiated in the bottom of the converter and continue therein until such time as the refractory material has reached the desired temperature.

It has been customary in the prior art when cracking hydrocarbon oils in the vapor phase to conduct the vaporized oil thru continuous tubular heating coils wherein the vaporized oil may be subjected to relatively high temperatures, around 1200° F. for example. Heating the vapors in tubes or coils in this way has been attended with considerable difficulty particularly that of overheating of the tubes or pipes which must be exposed to relatively high furnace temperatures in order to heat the vapors flowing thru the tubes to the desired temperatures. Since the rate at which heat may be transferred from the walls of the tubes or pipes to the vaporous material flowing therethru is relatively low, the tube walls are therefore subject to relatively severe heating which results in rapid deterioration of the metal and consequently shortens the life of the tube or pipe in service. A further difficulty is the readiness with which carbon is deposited on the interior surfaces of the tubes particularly when the material flowing thru the tubes is not in a completely vaporized state and therefore includes particles of liquid which when precipitated against the highly heated metallic surfaces are largely decomposed to form coke which adheres to the surface of the metal and tends to build up and form such a deposit that the tendency towards the overheating of the tubes is very greatly increased. For this reason it has been extremely essential heretofore in this type of cracking operation to employ only relatively light charging stocks such as kerosene and relatively low boiling gas oils.

In our invention where the vaporized oil is sub-

jected to conversion in a series of regenerative heating stoves or converters containing flues or checkerwork formed from an inert or refractory heat retaining material the vapors may be subjected to cracking temperatures for a prolonged period of time without subjecting the equipment to appreciable deterioration from severe and extended heating. Such carbon as may be formed during the conversion deposits upon the surfaces 5 of the refractory material and when the stoves are successively cut out of service for reheating the deposited carbon is readily and advantageously removed by combustion during the reheating step during which the heat retaining material is restored to a highly heated condition.

A further advantage of our invention is the possibility of maintaining continuous operation for substantially indefinite periods of time. That is, when employing a plurality of converters in 10 which to carry on the conversion of the oil there may be only an inappreciable accumulation or deposition of carbon upon the refractory material during the relatively short period of time that each converter remains on the line between 15 reheatings, and this carbon deposit is readily removed by combustion during the reheating step so that no operating delay is necessary to remove the carbon, and which is to be contrasted with the cracking of hydrocarbon vapors in a pipe 20 coil heater where it is necessary to shut down at quite frequent intervals in order to manually remove the coke which has become deposited within 25 the pipes or tubes.

A further feature of our invention comprises 30 continuously forming a clean circulating stock free from tarry or residual pitchy matter which might otherwise be readily decomposed to form substantial quantities of coke during passage of the oil thru the conversion zone.

These and other objects and advantages of 35 the invention will be better understood from the following description considered in connection with the figures of the accompanying drawings which illustrate diagrammatically a preferred 40 form of apparatus for practicing the process of the invention.

In the drawings, Figure 1 is a diagrammatic 45 elevational view illustrating apparatus adapted to the carrying out of the process of the invention.

Figure 2 is a diagrammatic view in plan illustrating a method of interconnecting the converters.

Referring to Figure 1, a pump 1 draws oil from 50 a source (not shown) and pumps the oil thru a line 2, having a valve 3, leading to a reflux coil 4 located in the upper portion of a fractionating column 5 and adapted to supply cooling thereto. A by-pass 7, having a valve 8, is provided thru 55 which oil not required to go thru the reflux cooling coil may be passed directly into a pipe 6 leading from the outlet of the reflux coil 4 to a heat exchanger 9 thru which latter the oil flows in indirect heat relationship with a stream of residual oil being withdrawn from the system. A by-pass pipe 10 is also provided to permit bypassing the exchanger 9. From the exchanger 9 60 the heated oil flows thru a pipe 11 leading to the upper portion of a stripping tower 12 into the interior of which it is introduced thru a spray 13 adapted to distribute the oil over suitable packing material 14 such as rocks, raschig rings, bubble trays, tiles and the like.

Hydrocarbon vapors which have previously undergone cracking as will presently be described

are introduced to a lower portion of the stripping tower 12 thru a transfer line 15, after flowing either totally or in part thru a coil 16 located in the bottom of the stripping tower and adapted to supply heat for reboiling the liquid collecting in the bottom of the tower. The cracked vapors in passing upwardly thru the packing material 14 come into intimate and direct contact with the downwardly flowing charge oil thereby cooling and partially condensing the vapors and vaporizing the bulk of the charge oil. The liquid collecting in the bottom of the stripping tower 12 which is composed of the unvaporized residual portions of the charge and tarry material condensed out of the cracked vapors is withdrawn thru a pipe 17, having a valve 18, to the heat exchanger 9 in which it is cooled while imparting its sensible heat to the incoming charge. A portion of the liquid being withdrawn thru the pipe 17 may be conducted thru a pipe 19, having a valve 20, leading to a coil 21 placed in the bottom of the fractionator 5 adapted to supply heat for reboiling the liquid condensate collecting in the bottom of the fractionator and thereby facilitate fractionation within the tower. The oil leaving the coil 21 is preferably returned thru a pipe 22 to the heat exchanger 9 from which it may be withdrawn and disposed of as may be desired.

The vapor mixture rising to the top of the stripping tower 12 is conducted thru a pipe 23 to the middle portion of the fractionator 5 wherein it is subjected to fractionation to form a vapor fraction, consisting of gasoline and fixed gases, and a relatively higher boiling liquid fraction collecting as a reflux condensate in the bottom of the fractionator. The gasoline vapor is withdrawn from the top of the fractionator 5 thru a pipe 24 leading to a condenser 25 wherein it is cooled and condensed to form a distillate which is withdrawn thru a pipe 26 leading to an accumulator or receiving drum 27 wherein the non-condensable fixed or dry gases are separated from the gasoline liquid to be withdrawn thru a pipe 28 while the gasoline liquid may be withdrawn thru a pipe 29 to storage or for further treatment.

The surplus reflux condensate collecting in the bottom of the fractionator 5 and which is composed of the fresh gas oil portion of the charge in admixture with the partially converted oil 50 condensed out of the cracked vapors, forming a clean circulating stock for vapor phase cracking, is withdrawn thru a pipe 30 and conducted by means of a pump 31 thru a line 32 leading to a pipe coil 33, in a suitable furnace 34, and wherein the stock is heated to a vaporizing temperature, preferably under superatmospheric pressure.

The heated oil is discharged from the heating coil thru a pipe 35, having a valve 36, into a vaporizing chamber 37 preferably maintained at 60 a pressure lower than that maintained in the heating coil. Upon introduction to the vaporizer 37 the heated material is substantially entirely flashed to a vapor which is withdrawn thru a pipe 38 leading to the first of a series of converters 39. The unvaporized oil collecting in the vaporizer 37 may be withdrawn thru a pipe 40, having a valve 41, by means of a pump 42 which discharges it into a pipe 43 leading to the pipe 11, already mentioned, and wherein this unvaporized oil is admixed with incoming charge and returned to the system for further treatment.

If desired, this unvaporized oil may be conducted thru a pipe 44, having a valve 45, leading to an atomizer or jet nozzle 46 interposed in the 75

vapor line 38. The velocity of the vapors flowing thru the atomizer 46 may be sufficiently high to entrain the liquid, which is usually relatively small in amount, and convert it to a mist of finely divided form.

The vaporized oil enters the lower portion or combustion chamber 47 of the first converter and flows upwardly thru a flue 48 to the top of the converter from which point the vapors pass downwardly thru highly heated checkerwork material 49 and as a result of intimate contact with this refractory material the vapors are heated to a suitable cracking temperature. From the bottom of the checkerwork the vapors are passed thru a pipe 52 to the inlet of the next succeeding converter. From the bottom of the last converter the cracked vapors are passed into the transfer line 15, already mentioned, and which leads to a mid point of the stripping tower 12.

Referring to Figure 2, the vaporized oil flowing thru the pipe 38 is conducted to a manifold 60 with branch pipes 61, 62, 63 and 64, each having a valve 65, leading to the pipes 51, 52, 53 and 54, each having a valve 55, interconnecting the four converters 39a, 39b, etc. Vapor discharge lines 66, 67, 68 and 69, each having a valve 70, connecting with the pipes 51, 52, etc. form vapor outlets for each converter leading to a main vapor line 71 from which the vapor stream is conducted thru the transfer pipe 15 to the stripping tower as already described. Purging out pipes 12, 73, 74 and 75, each having a valve 76, are provided thru which vapor remaining in any stove after it has been cut out of the system for reheating may be displaced to a suitable gasometer 77 in which the heavier portions of the vapor may condense and be withdrawn therefrom thru a pipe 78 for subsequent return to the system. The uncondensed gaseous material remaining in the gasometer is available as fuel gas for combustion purposes during the reheating operation and which gas is conducted thru a pipe 79 leading to fuel gas inlets or burners 80 provided with air inlets 81, and extending into the combustion chambers 47 of each of the converters.

When operating with four converters as illustrated in the diagram and where the vapors are flowing thru three of the converters in succession while the fourth is being reheated, the vapors may, for example, enter the combustion chamber 47 of the coolest converter 39a from the manifold 60 thru the pipe 61. After passing downward thru the checkerwork in this converter the vapors pass thru the connecting pipe 52, to the combustion chamber of the next succeeding and hotter converter 39b and from which, after passing therethru, they flow thru the pipe 53 to the third and hottest converter 39c from which the cracked vapors are then passed thru the pipe 68, leading from the pipe 54, and are conducted into the main vapor line 71 leading to the transfer line 15.

The converter 39d may be segregated or isolated from the series in order to undergo reheating by closing the valves 65 and 55 in the pipes 64 and 54, respectively, and also closing the valves 55 and 70 in the pipes 51 and 69, respectively. At the time of segregating it from the rest of the converters it will, of course, be filled with partially converted vaporized material and upon cutting it out of the system these rich hydrocarbon vapors may be displaced from the converter by introducing fuel gas, or preferably the fixed or dry gases which have been generated

in the process and which may be withdrawn under pressure from the pipe 28 leading from the accumulator drum 27, thru the pipe 79 and the burner 80 to the combustion chamber of the converter. The fixed gases in flowing thru the checkerwork displace the richer hydrocarbon vapors thru the pipe 75 leading to the gasometer 77.

As soon as these rich vapors have been substantially completely displaced from the converter the necessary amount of air may then be introduced thru the burner extending into the combustion space of the converter and combustion of the entering dry gas initiated. The supply of air may be regulated so as to substantially confine the flame to the combustion chamber and from which the hot products of combustion pass upwardly thru the interior flue 48 and then pass downwardly thru and over the checkerwork to heat it up, the period of combustion being prolonged for a sufficient time, preferably for not over an hour, to heat up the refractory material to the desired temperature which will usually range from about 1300° to 1400° F. The hot flue gas leaving the converter during the reheating step may be discharged into a flue 82 leading to a stack 83 thru which it may be discharged to the atmosphere, although advantage may be taken of its sensible heat content by returning a portion of the hot flue gas by means of a fan 84 thru a pipe 85 to the furnace 34.

When the refractory material has attained the desired temperature the flow of air to the burner 80 may be stopped thus extinguishing the flame 35 and terminating combustion whereupon the valve 55 in the pipe 54 and the valve 65 in the pipe 64 may be opened and also the valve 70 in the pipe 68 closed allowing the hot vapors from the converter 39c to enter the newly heated converter 39d and pass therethru into the pipe 69 leading to the main vapor line, the valve 70 in the pipe 69 being opened substantially simultaneously with the closing of the valve 76 in the purging out line 75. The converter 39a now being the coolest converter is cut out of the system and reheated in a manner similar to that just described.

In the practice of our invention a charge stock, which may comprise crude oil, after being pre-heated during passage thru the reflux coil 4 and the heat exchanger 9, is introduced to the stripping tower 12 wherein it is commingled with a stream of vapors previously subjected to cracking in order to condense undesirable tarry constituents out of the vapors as well as to effect distillation of the substantial bulk of the crude. The tarry matter condensed out of the cracked vapors together with the residual portion of the crude collecting in the bottom of the stripping tower 12 may be withdrawn from the system as a fuel oil or to be used in any other desirable manner.

The resulting vapor mixture comprising the partially cooled cracked vapors and the natural gasoline and gas oil fractions of the crude charge is introduced thru the pipe 23 to the fractionator 5 wherein it is subjected to fractionation to form a vapor fraction composed of the natural gasoline constituents of the charge and those fractions of the converted material having the same boiling range as gasoline as well as the fixed gases generated during conversion. This resulting gasoline vapor fraction is then subjected to cooling and condensing following which it is drawn off 75

to the accumulator drum 27 wherein the fixed gases are separated from the gasoline distillate.

That portion of the crude charge exclusive of its natural gasoline constituents and comprising 5 fresh gas oil which is condensed in the fractionator 5 together with the relatively high boiling and partially converted portions of the cracked vapors, is withdrawn thru the pipe 30 and pumped thru the pipe 32 to the heating coil 33 wherein 10 it is heated to temperatures of around 700° F. or higher and preferably under pressures which may range from somewhat above atmospheric to 400 or 500 pounds or even higher. The heated oil is expanded thru the valve 36 into the vaporizing 15 chamber 37 which may be maintained at a pressure substantially lower than that within the heating coil in order to facilitate substantially 20 entirely complete vaporization of the heated oil. It is contemplated that the conditions of temperature and pressure may be regulated to whatever extent is necessary in order to effect substantially 25 complete vaporization upon introduction to the vaporizing chamber.

It is desirable to introduce the hydrocarbon oil 25 to the converters in a completely vaporized condition since when substantial amounts of liquid in the form of droplets or particles are introduced to the conversion zone wherein the particles come into contact with the refractory material a rapid 30 decomposition of the liquid particles may take place with the production of substantial amounts of coke. The decomposition of liquid into coke under these conditions is believed to take place to a materially greater extent than is the case 35 with oil which is entirely in the form of vapor or as a fine mist.

While the vaporizing oil may in many cases be introduced directly from the coil outlet to the 40 first converter which is under sufficiently lower pressure than the heating coil to result in sufficiently complete vaporization of the oil upon its introduction to the converter, means have been provided to facilitate separation of liquid particles from the vapor prior to its entry to the conversion zone. This unvaporized material may be 45 withdrawn from the bottom of the vaporizing chamber and be either admixed with the fresh charge entering the system or passed thru the atomizing means 46 wherein advantage may be taken of the atomizing effect of vapors flowing 50 thru the atomizer at a high velocity to convert this liquid, which under ordinary conditions is of relatively small amount, to a sufficiently fine state of division such that its introduction to the converters is not attended with a substantial amount of 55 decomposition to form coke or carbon.

The vaporized oil may enter the first converter of the series at a temperature of from 700° to 800° F. and in passing thru the heated checkerwork 60 of this converter may be heated to from 900° to 1000° F. From this converter it flows thru the second or intermediate and next hottest converter of the series wherein the vapors may be heated to from 1000° to 1100° F. while in the third and hottest converter they may be raised to a temperature of from 1100° to 1300° F. The degree and frequency of reheating of the converters 65 may be regulated so that the temperature of the vapors finally leaving the conversion zone may be consistently around 1200° F., although higher temperatures may readily be maintained merely by increasing the temperatures of the refractory material to whatever temperature is necessary to impart the desired amount of heating to the 70 vapors. By flowing the vapors thru a plurality of

converters arranged in series the temperature of the vapor leaving the last converter may be maintained substantially uniform without material variations therein due to periodically cutting out one converter for reheating and cutting into the 5 series a newly reheated converter. Furthermore, the vapors are subjected to a substantial period of digestion at high temperatures when flowing thru the series of three or more converters in succession, which extended time of digestion is desirable from the standpoint of extending the degree of the conversion reaction, that is, to increase the amount of cracking with the consequent production of larger yields of gasoline or motor fuel from the charging stock. Such increased digestion may also be desirable from the standpoint of affording a stabilization of the reaction products thereby resulting in an improved and more stable final product.

Although the treatment of crude petroleum 20 has been described above in more or less detail the process of the invention is not limited to the charging of this type of oil but is adapted to handling various types of charging stocks such as topped crude or gas oils of relatively high 25 boiling range as well as relatively lighter stocks such as kerosene.

It is contemplated that any desired pressure 30 may be employed and that a uniform pressure may be maintained throughout the entire system, although ordinarily it may prove more desirable to maintain the heating coil or pipe still under superatmospheric pressure, releasing the pressure somewhat in the vaporizing chamber, maintaining a reduced superatmospheric pressure in the converters, and reducing the pressure still further or to approximately atmospheric pressure in the dephlegmating means.

Obviously many modifications and variations 40 of the invention, as hereinbefore set forth, may be made without departing from the spirit and scope thereof, and therefore, only such limitations should be imposed as are indicated in the appended claims.

We claim:

1. The process of treating hydrocarbon oil 45 which comprises passing a clean relatively heavy oil through a heating zone wherein it is raised to a vaporizing temperature, separating the resulting heated oil into vapors and a liquid residue, passing said vapors through a converter zone in contact with highly preheated solid refractory material wherein said vapors are raised to a cracking temperature controlled independently of said vaporizing temperature and are 50 subjected to conversion by the contained heat of said preheated refractory material, removing resulting cracked products and introducing them into a separating zone wherein vapors separate from liquid residue, removing vapors from the 55 separating zone and passing them directly into a fractionating zone independent of said heating zone, wherein desired constituents separate as vapors from undesirable heavy products as reflux condensate, removing the fractionated vapors and condensing them to form a desired product, removing reflux condensate so formed and passing it through said heating zone as 60 said clean oil first mentioned and introducing fresh relatively heavy charging stock into said 65 separating zone in contact with the introduced cracked products to cause at least partial vaporization of said charging stock, and removing liquid residue from said separating zone.

2. A process in accordance with claim 1 where-

in liquid residue left after separating vapors from the heated clean oil removed from the heating zone, is introduced into said separating zone in contact with the hot cracked products introduced thereto from the converter zone.

5. A process in accordance with claim 1 where-

in liquid residue left after the separation of vapors from the heated clean oil removed from the heating zone is introduced in mist form into said converter zone.
